UNITED STATES PATENT OFFICE.

FRANK E. BAKER, OF SYRACUSE, NEW YORK, ASSIGNOR TO CHAPIN-SKELTON CORPORATION, OF SYRACUSE, NEW YORK, A CORPORATION OF NEW YORK.

GARMENT-PRESSING MACHINE.

Application filed December 8, 1924. Serial No. 754,630.

To all whom it may concern:

Be it known that I, FRANK E. BAKER, a citizen of the United States of America, of Syracuse, in the county of Onondaga, in the 5 State of New York, have invented new and useful Improvements in Garment-Pressing Machines, of which the following, taken in connection with the accompanying drawings, is a full, clear, and exact description.

10 This invention relates to certain improvements in garment pressing machines involving the use of cooperative pressing elements one of which is movable toward and from the other together with means for supplying 15 steam to the garment for moistening and sterilizing purposes.

In machines of this character it is desirable to remove the steam and moisture of condensation from the garment as soon as 20 possible after the moistening and pressing operation to not only reduce the escape of steam into the room in which the machine is located but also to effect a quick drying and cooling of the steamed and pressed garment and to be able to produce a more effective and permanent shaping of the garment following the steaming and pressing operations.

I am aware that certain devices have heretofore been proposed for removing the steam from the garment following the steaming and pressing operation but in all such devices with which I am familiar it has been necessary to employ two or more controlling 35 valves, one for the admission of steam to the garment and the other for controlling the suction for withdrawing steam and moisture from the garment.

The main object of this invention is to 40 control the passage of steam to the garment and the withdrawal of the steam and moisture from the garment by one and the same valve, another object to utilize a portion of this valve as a part of an ejector for receiving 45 steam from the same source of supply as that used for moistening purposes for producing the desired suction for withdrawing the steam and moisture from the garment. In other words, I have sought to produce 50 three effects or results through the use of a single valve viz.,

1. Controlling the supply of steam to the garment,
2. Utilizing a portion of the valve as an 55 ejector, and

3. Utilizing the ejector for suction purposes for withdrawing steam and moisture from the garment.

Other objects and uses relating to specific parts of the device will be brought out in the 60 description.

In the drawings:

Figure 1 is a sight elevation, partly broken away and partly in section, of a garment pressing machine showing my improved valve mechanism operatively mounted thereon.

Figure 2 is a top plan, partly in section of the detached buck showing a portion of the heating chamber and steam passages leading 70 thereto and therefrom.

Figure 3 is an enlarged longitudinal, vertical sectional view of the detached valve mechanism for controlling the application and withdrawal of the steam to and from 75 the garment.

Figure 4 is an enlarged longitudinal vertical sectional view of the same valve taken in the plane of line 4-4, Figure 5.

Figure 5 is a horizontal sectional view 80 taken in the plane of line 5-5, Figure 3.

In order that the invention may be clearly understood I have shown a pedestal —1— adapted to be mounted upon a floor or other suitable support for receiving and supporting at its upper end a rock arm —2— carrying at its front end a press head —3— which is movable toward and from an underlying buck —4—, said buck being mounted upon a bracket —5— forming a part of the main 90 supporting frame or pedestal —1—.

The buck —4— is provided with a heating chamber —6— extending entirely around its marginal edge from opposite sides of a partition —7— which preferably is located some distance from the ends of the buck to cause the live steam to pass from end to end of the channel or chamber, one end of the channel being connected to a steam inlet —8— while the other end is connected to an outlet passage —9—, said passages —8— and —9— being located at opposite sides of the partition —7—.

The inlet —8— may be connected to any source of steam supply while the outlet 105 —9— may be connected to a waste pipe if desired. The buck —4— is also provided with a steam distributing chamber —10— communicating with suitable discharge openings —11— in the upper face thereof 110

for supplying steam to the garment for moistening and sterilizing purposes.

The steam distributing chamber —10— is connected by a pipe —12— to a valve case —13— which in turn is supported by a suitable bracket —14— upon the main frame —1— directly below the buck —4—. The valve case —13— is preferably composed of two sections —15— and —16— firmly bolted together face to face by clamping screws —17— to form a steam tight joint between them.

The section —15— is provided with two ports —18— and —19— in vertically spaced relation, the port —18— being connected to the steam pipe —12—, while the port —19— is connected to a waste pipe —20— leading to the exterior of the building or to a suitable soil pipe, not shown. The section —16— is provided with a steam chamber —21— having an inlet port —22— adapted to be connected by a pipe —23— to any available source of steam supply, said chamber —21— being elongated vertically and extended some distance beyond the ports —18— and —19— for receiving a slide valve —24— which is spring pressed against the flat inner face of the section —15— by bow springs —25— to form a steam tight joint therewith and is provided with a pair of ports —26— and —27— in vertically spaced relation corresponding to the distance between the ports —18— and —19— with which they are adapted to register respectively when the valve is adjusted to its suction producing position. The slide valve —24— is also provided with a passage —28— connecting the ports —26— and —27—.

The portion of the valve —24— at the inner side of the passage —28— is provided with a nozzle —29— extending into, but of less diameter than the port —27— so as to leave a greater open space between said nozzle and walls of the port —27—, said nozzle being provided with a restricted steam passage —30— therethrough in communication with the steam chamber —21— for receiving steam therefrom and discharging said steam into the port —19— and waste pipe —20— when the nozzle is registered with the port —19—.

The distance between the ports —26— and —27— is substantially equal to the distance between the ports —18— and —19— and greater than the distance between the upper port —26— and upper end of the valve so as to permit the ports —26— and —27— to be closed by the adjacent section —15— when the valve is moved downwardly a sufficient distance to expose the port —18— to the steam chamber —21— above the upper end of the valve for admitting steam from said chamber to the port —18— and thence through the pipe —12— to the distributing chamber —10— of the buck —4— for moisten-

tening the garment which may be interposed between the buck and press head.

The means shown for adjusting the valve endwise consists of a rod —31— having its lower end secured at —32— to the inner side 70 of the valve and its other end extending upwardly through a suitable gland —33— in the upper end of the section —16— for connection to a suitable operating lever —34—.

This lever is fulcrumed at —35— to the upright standard and extends forwardly therefrom across and beyond the upper end of the rod —31— to which it is connected by a bolt —36— passing through an elongated slot —37— in said lever, the front end of the lever being provided with a suitable handle —38— within convenient distance of the operator and preferably directly below the buck —4—.

Operation.

When it is desired to introduce steam into the garment under pressure between the pressing elements the valve —24— will be adjusted downwardly to the position shown by dotted lines in Figure 3 by simply depressing the hand lever —34— from a position shown by full lines to the position shown by dotted lines in Figure 1 until the upper end of the valve —24— registers with or is in a plane more or less below the upper edge of the port —18— in which position the ports —26— and —27— of the valve will be closed by the adjacent section —15— thus permitting the passage of steam from the inlet —23— into the port —22— and chamber —21— and thence over the top of the valve through the port —18— and upwardly through the conduit —12— to the distributing chamber —10— of the buck —4— 105 which in turn enables the steam to escape through the passage —11— to the garment on the buck.

As soon as the steaming and pressing operations are completed the valve —24— is returned to its normal up position shown by full lines in Figure 3 thereby registering its ports —26— and —27— with the ports —18— and —19— respectively and at the same time registering the ejector passage —30— with the port —19— to allow the steam from the chamber —21— to pass directly through the restricted passage —30— and thence into the conduit —20— for producing suction in the port —27—, conduit —30—, port —31— and pipe —12— and also in the distributing chamber —10— connected to said pipe, the suction thus produced serving to withdraw the steam and moisture from the garment for drying the same almost instantly upon the creation of the suction.

Under this construction it is evident that the single valve —24— serves the triple purpose of controlling the supply of steam to 120

the garment, creating a suction in the passages leading to the distributing chamber of the buck and withdrawing the moisture from the previously steamed and pressed garment, 5 and while I have shown the valve case and valve as arranged in an upright position or vertical position as the most direct means for connection with the buck it is evident that the position of the valve case and construction of the valve may be varied without departing from the spirit of the invention.

What I claim is:—

1. In a garment pressing machine, a valve chamber having a steam inlet and separate ports, one of said ports being an exhaust port, the other port admitting steam to and receiving steam and moisture from the garment, and a valve adjustable to one position 15 for closing the exhaust port and opening the other port to permit the passage of steam to the garment, and to another position for connecting both ports, said valve having means for admitting steam from the valve 20 chamber through the exhaust port when the valve is in the second named position.
2. In a garment pressing machine, a valve chamber having a steam inlet and separate ports, one of said ports being an exhaust 25 port, the other port admitting steam to and receiving steam and moisture from the gar-

ment, and a valve adjustable to one position for closing both of said ports, to another position for closing the exhaust port and opening the other port to permit the passage 35 of steam from the valve chamber to the garment, and to a third position for connecting both ports, said valve having means for admitting steam from the valve chamber to the exhaust port when the valve is adjusted to 40 the third named position for withdrawing the steam and moisture from the garment.

3. In a garment pressing machine a device for controlling the supply of moisture to and withdrawing it from the garment, 45 comprising a valve chamber having an exhaust port and an additional port through which the moisture is supplied and withdrawn to and from the garment, means for admitting steam to the valve chamber, and a 50 valve slideable in said chamber and adjustable to one position for closing the exhaust port and opening the other port, and to another position for connecting both ports, said valve having a steam jet communicating 55 with the steam chamber and discharging directly into the exhaust port when the valve is adjusted to the second named position.

In witness whereof I have hereunto set my hand this 1st day of December 1924.

FRANK E. BAKER.
